United States Patent Office.

LEWIS GIBBS, OF CANTON, OHIO.

Letters Patent No. 93,079, dated July 27, 1869.

IMPROVED SASH-HOLDER.

The Schedule referred to in these Letters Patent and making part of the same.

To all whom it may concern:

Be it known that I, LEWIS GIBBS, of Canton, in the county of Stark, and State of Ohio, have invented new and useful Improvements in Sash-Fastenings; and I do hereby declare that the following is a full, clear, and exact description of my invention, reference being had to the accompanying drawings, forming a part of this specification, and to the letters of reference marked thereon, of which drawings—

Figure 1 is an elevation of a window-frame and sash, with my improved fastening applied thereto.

Figure 2 is another elevation, showing the mode of supporting the sash.

Figure 3 is a sectional plan of the same, with sash locked down.

Figures 4 are front elevation and plan of the sliding lock-bolt.

Figures 5 are front elevation and sectional side view of the case.

Figures 6 are front elevation and sectional side view of the retaining-shell.

The nature of my invention consists—

First, in the novel construction of a device for supporting window-sashes, said device consisting of a circular-formed metallic case, which has within it a retaining-shell, having its back formed to the same curve as that of the inner face of the case, and its face formed into such a curve, as that it shall act as a cam around the axis of the case, and against the window-frame, the case and retaining-shell being so constructed, as that the movement of the retaining-shell in the case is effected by the sliding of the shell within the case, and not by any rolling of said shell on the inner face of the case, nor by the rotation of said shell around an axle-pin in the sash-case, as has been the practice in previous devices of this class.

The peculiar utility of this mode of construction consists in the simplicity and ease with which the device can be applied to the sash, the only tools required being a bit or auger, to bore the hole in the sash, and a hammer to drive the case into said hole, where it is held without the aid of screws or any like devices; and the second advantage being in the extreme lightness and consequent cheapness of the case and shell required, as the case is reinforced around its entire edge, by its bearing against all parts of the hole in the sash in which it is inserted, while the retaining-shell has a bearing on the whole of its back against the inner face of the case, when under pressure in sustaining the sash, instead of throwing the whole strain on to an axle-pin or a light seat, as in previous devices of this class, and hence has great capacity to resist the strain brought to bear on it.

The nature of my invention consists—

Secondly, in the combining with the case and retain-

ing-shell, constructed as described, a sliding bolt, by means of which the retaining-shell is easily manipulated, and the sash can be securely locked at any desired point in the window-frame, whereby I obtain a very cheap and efficient fastening for locking or supporting the sash.

To enable others skilled in the art to make and use my invention, I will proceed to describe its construction and operation.

The case B of my fastening is made in the circular form shown, with its exterior surface sloping in the form of a conic frustum, from the face of the case to its back, as shown in side view in figs. 5.

On the sides of the case are arranged one or more sharp wedge-shaped flanges, f f, which prevent the case from turning in the hole in the sash.

The plate C, which forms the face of the case, is raised above the plane of the body of the case, and is of such size as to leave a space, E, between its edge and the rim of the case, as shown in figs. 5.

The retaining-shell F is constructed with its back curved to a circle of the same diameter, x, as that of the interior of the case B, while its face is made in the general form of an ellipse, as shown in figs. 6, the smaller axis of the ellipse being of such length, as that the shell, when setting squarely in the case, shall have its front face about flush with the open sides of the case, as seen in fig. 3.

The shell shown in drawings is made with a raised rim, h, around its face, which falls off to the frame of the shell, near its back, said back being about one-half the height of the full shell, and a depression, G, is formed in the shell-frame, in which works the bolt A.

This bolt A consists of the bolt proper, a, which is flattened out and turned up into the arm b, to which is secured the plate c, which projects outside the case B, and has a knob, K, attached to it, as shown.

These three parts fit together, as shown in fig. 3, the arm b of the bolt A working around in the space E in the case B, and the bolt a sliding in the depression G in the shell B, while the flattened rear portion of the bolt a fits between the flanges h h, which are carried along at each side of the depression G, thus causing the rotary movement of the bolt A to communicate a similar movement to the shell F.

The case B is secured in the sash H, by first boring a hole in said sash of about the diameter of the small end of the exterior of the case, and in such a position as to bring the straight and open side of the case B flush with the edge of the sash H, and then driving the case into such hole, where it is firmly retained by its close fit in the hole, due to its wedge-shaped form, and is prevented from turning by the flanges f, which are forced into the wood by the driving of the case into the sash.

The retaining-shell F and bolt A are placed in the case B before it is driven into the sash, and are thus secured in their proper working-position.

The raised portion c of the case B is so arranged as to just fit up to the sash-strip N, as seen in fig. 1.

The sash H is supported at any point, by drawing down the knob K, so as to turn the shell F out of its square position in the case, thus bringing its lower surface against the window-frame L, and causing it to act as a cam between said frame and the case B and the sash H, when it is evident that the weight of the sash will act to tighten the cam as it presses downward, and that the sash will be securely supported.

The sash can be lowered, by raising it a little, so as to loosen the cam-action of the shell F, when, by means of the knob K, this shell can be held in its square position in the case B, and the sash lowered, as desired.

It is evident that the sash could be locked down by drawing up the knob K, and bringing the upper face of the shell F against the frame L; but for greater security, a hole, n, is bored in the frame L, into which the bolt a is shot by means of the knob K, the bolt being prevented from turning with the shell F in the case B, by a flange, d, secured on the part c, which slides into a slot, D, in the plate C, as the bolt is being shot into the hole n.

It is evident from the foregoing description, that a cheap form of fastening, constructed on the plan herein shown, could be made by making the case B without the covering-plate C, and with a flange around its edge, to hold the shell in the case, the bolt A being omitted, and the shell F being operated, by grasping the flanges h h at the sides of the depression G, in a manner readily seen; or the covering-plate C could be made flush with the edges of the case B, and a knob could be cast on the shell F, which should project through the space E, and by means of which the shell F could be operated.

The case, retaining-shell, and sliding bolt, can be cast of common cast or malleable iron, or of other suitable material, and the face of the case B, as well as the plate C and knob K of the bolt A, may be ornamented as desired.

Having thus fully described my invention, I do not

claim as new the use of a rolling retaining-shell in a case inserted in the sash, for the purpose of supporting said sash, when said shell is made in a cylindrical form, and is arranged to roll on the inner face of the case, or is pivoted on an axle-pin in the sash-case, and is arranged to turn thereon; nor do I claim the use of a sliding lock-bolt in any other sash-fastening than that herein described, as these features have been before shown; but

What I do claim as new, and desire to secure by Letters Patent, is—

1. The combination of the circular sash-case B and retaining-shell F, when said retaining-shell is so constructed as that its back shall fit the inner face of the sash-case, and its movement shall be effected by its sliding within the sash-case, instead of rolling therein, or turning on an axle-pin, substantially as is herein specified.

2. The sliding bolt A, when used in combination with the retaining-shell F, which is fitted to the sash-case B, and slides on the inner face thereof, instead of rolling thereon or turning on an axle-pin, substantially as and for the purpose herein specified.

3. The flange d on the sliding bolt A, when used in combination with the slot D in the case B, substantially as and for the purpose specified.

4. The case B, provided with the raised plate C, when used in combination with the retaining-shell F and sliding bolt A, substantially as and for the purpose herein specified.

5. The improved sash-supporter and lock herein described, consisting of the case B, with flanges f and raised plate C, with slot D, retaining-shell F, and sliding bolt A, with flange d, the several parts being constructed, combined, and operating substantially as and for the purpose specified.

As evidence that I claim the foregoing, I have hereunto set my hand, in the presence of two witnesses, this 27th day of May, 1869.

LEWIS GIBBS.
